UNITED STATES PATENT OFFICE.

CARL FRED SAMMET, OF ANNANDALE, NEW JERSEY, ASSIGNOR TO EMIL SAMMET, OF ANNANDALE, NEW JERSEY.

MUSIC-LEAF TURNER.

1,154,342.

Specification of Letters Patent. Patented Sept. 21, 1915.

Application filed June 29, 1914. Serial No. 848,007.

To all whom it may concern:

Be it known that I, CARL FRED SAMMET, a citizen of the United States, residing at Annandale, in the county of Hunterdon and State of New Jersey, have invented certain new and useful Improvements in Music-Leaf Turners, of which the following is a specification.

This invention relates to a music leaf 10 turner which is intended to be connected with a piano of the upright type and the principal object of the invention is to provide a music leaf turner having an improved manner of mounting the leaf engaging 15 arms and to also provide improved actuating means for moving these arms.

Another object of the invention is to provide a stem which forms a portion of the actuating means with an improved manner 20 of mounting so that as the same moves longitudinally it will have a rotary motion, thus causing the leaf engaging arms to be moved.

Another object of the invention is to so 25 construct the support of the leaf engaging arms and stem that the support may be removed when it is not desired to use the same.

Another object of the invention is to so 30 construct the device that it will be very simple in construction but at the same time very efficient in operation.

This invention is illustrated in the accompanying drawings, wherein—

35 Figure 1 is a view showing a piano in front elevation and provided with the improved leaf turning attachment; Fig. 2 is a view showing the piano in end elevation and provided with the improved leaf turning 40 attachment; Fig. 3 is a perspective view of the support which is removably connected with the piano; Fig. 4 is a fragmentary view showing the manner of mounting the finger which engages the leaf engaging 45 arms; Fig. 5 is a fragmentary sectional view taken along the line 5—5 of Fig. 1.

The piano 10 is of the usual construction of upright pianos and is provided with a socket 11 which is secured to the top as 50 shown in Figs. 1 and 2. The book supporting bracket 12 is connected with the foot 13 of the supporting bar or strip 14 by means of a bolt 15 which serves another purpose to be hereinafter brought out. This strip 14

is connected with the strip or wedge 16 55 which fits into the socket 11 to support the leaf turning mechanism in the position shown in Figs. 1 and 2. The forward end 17 of the wedge 16 extends beyond the strip 14 and is provided with an opening which is 60 formed in alignment with an opening 18 formed in the upper arm 19 of the guiding strip 20. This guiding strip 20 is secured to the supporting strip 14 and has its lower end bent to form a foot 21 which is positioned above the foot 13 of the strip 14.

The leaf engaging arms 22, 23 and 24 are pivotally mounted upon the bolt 15 between the feet 13 and 21 and are separated by the dividing plates 25 and 26 which are positioned as shown in Fig. 5 with their rear ends passed through openings 27 and bent to lock the plates stationary. The inner end of the arm 23 is provided with a heel 28 which extends to such an extent that the 75 heel will be engaged by the arm 22 when swung to the position shown in Fig. 3 and cause the arm 23 to be moved forward slightly. When the arm 23 is swung to turn the page which it engages, the heel will engage the arm 24 and move it forwardly 80 slightly. This is done to bring the arms in the proper position to permit them to be swung upon the pivot bolt 15 and turn the pages.

In order to swing the arms, there is provided a stem 29 which is slidably mounted in the openings formed in the wedge 16 and arm 19 and has its lower end portion flattened and twisted as shown at 30. The stem 90 is twisted as shown so that as the pin moves downwardly through the opening 18 the stem will be turned from the position shown in full lines in Fig. 3 to that indicated by dotted lines. An arm 31 extends from the 95 lower end of the stem 29 and carries a pivotally mounted finger 32 which swings freely in one direction but is limited in its pivotal movement in the opposite direction by means of an abutment 33 shown in Fig. 100 4. It will thus be seen that when the stem returns to the position indicated by dotted lines in Fig. 3 the finger 33 will carry one of the leaf engaging arms with it but that when moving in the opposite direction the 105 finger 32 will move pivotally and not move the second leaf engaging arm in case the finger strikes the second leaf engaging arm

when the stem is returning to the position shown in full lines in Fig. 3.

The lever 34 which forms part of the actuating mechanism is pivotally connected 5 with the piano by means of the bearing 35 and has its forward end provided with a slot in which the stem fits as shown in Figs. 1 and 2 so that when the lever is moved the stem will be moved with it. This lever 10 which is normally held in the position shown in Fig. 2 by means of the springs 36 is connected with a rod 37, the lower end of which is connected with the bell crank lever 38. This bell crank lever 38 is connected 15 with the foot treadle 39 by means of the rod 40 and it will thus be seen that when the foot treadle 39 is moved downwardly the bell crank lever 38 will be swung to raise the rod 37 and swing the lever 34 against the tension of the spring 36, thus moving the 20 free end of the lever downwardly and carry with it the stem 29.

When this device is in use, the actuating mechanism is permanently connected with 25 the piano and the music turning and supporting mechanism is only connected with the piano and actuating mechanism when it is desired to use the piano. After a book of music has been placed upon the support 12 30 the leaves of the book containing the piece it is desired to play are engaged by the arms 22, 23 and 24. After the first page of music has been played, the foot treadle 39 is pressed upon, thus moving the actuating 35 mechanism to depress the stem 29. It is of course obvious that when the mechanism is in the initial position shown in Fig. 1 the arm 22 will be in a position to permit finger 32 to pass between the arms 22 and 23. As 40 the stem 29 moves downwardly the finger 32 will first engage the arm 22 and the stem will then turn, thus swinging the arm 31 and causing the arm 22 to be moved to the position shown in Fig. 3. The foot treadle 39 is then released and the stem will be carried upwardly and return to the position shown in Fig. 3. When the arm 22 has moved to the position shown in Fig. 3 it will engage the heel 28 of the arm 23 and 45 swing it outwardly a sufficient distance to permit the finger 32 to engage the arm 23 when the actuating mechanism is again operated to move the stem 29 downwardly and turn the second page of the music. When 50 the second page of the music is turned the heel 28 will engage the arm 24 and move it to a position where it may be engaged by the finger 32. When it is no longer desired to use the piano the pin 16 is removed from 55 the socket 11 and the music supporting and turning mechanism will thus be disconnected from the piano and may be put away.

What is claimed is:—

1. A device of the character described 60 comprising a supporting strip, a supporting

bracket carried by said strip, a guide carried by said strip and provided with a rectangular opening, pivotally mounted leaf engaging arms, a pin connected with said supporting strips and having its outer end portion provided with an opening positioned above the opening of said guiding strip, a stem passing through the opening of said pin and having its lower end portion flattened to conform to the contour of said 70 guide and twisted to cause the stem to rotate when moved longitudinally, an arm extending from the lower end portion of said stem, a finger carried by said arm for engaging said leaf engaging arms and cause the same to be swung from one position to another, when said stem is moved downwardly, and means for moving said stem. 75

2. A device of the character described comprising a supporting element, a guide provided with a rectangular opening, attaching means for said supporting element provided with an opening formed in alignment with the opening of said guide, leaf engaging arms pivotally connected with said supporting element, a stem passing through the opening of said attaching element and rotating therein, the lower end portion of said stem being flattened and twisted and passed through the opening of said guide 90 to cause the stem to rotate and move longitudinally, means extending from said stem for engaging said leaf engaging arms to hold the same when said stem is moved downwardly, and means for moving said 95 stem. 100

3. A device of the character described comprising a support, pivotally mounted leaf engaging means, a guide positioned above said leaf engaging means and provided with a rectangular opening, an attaching member provided with an opening positioned above the opening of said guide, means for turning said leaf engaging means 105 slidably mounted in the openings of said guide and securing means, said turning means being twisted to cause the turning means to rotate when moved vertically, and means for moving the stem. 110

4. A device of the character described 115 comprising a support, pivotally mounted leaf engaging arms, one of said arms being provided with a heel to cause the same to be moved by a second arm when the second arm is moved to an adjusted position and to cause a third arm to be moved by the first mentioned arm when the first mentioned arm is moved to an adjusted position, means for turning said arms, and means for actuating said last mentioned means. 120

5. A device of the character described including a supporting strip having its free end bent to form a foot, a supporting bracket, a guiding strip carried by said supporting strip and having its lower end bent 125 130

- to form a foot extending above the foot of said supporting strip and having its upper end portion bent to form a guide, a pivot pin passing through said teeth and connecting said supporting bracket with said supporting strip, leaf engaging arms mounted upon said pivot pin, plates mounted upon said pin between said leaf engaging arms and having their inner end portions connected 10 with said supporting strip, a securing pin connected with the upper end portion of said supporting strip and having its forward end portion extending beyond the same, said guide and the forward end portion of said pin being provided with openings, a rod slidably mounted in said openings and positioned to cause the rod to rotate when moved longitudinally, and means connected with said rod for engaging said leaf engag-

ing arms and swing the same to an adjusted 20 position when the pin is moved downwardly.

6. A device of the character described comprising supporting means, leaf turning means, operating mechanism for said turning means and including a slidably mounted 25 stem, a pivotally mounted lever connected with one end portion of said stem, resilient means yieldably holding said lever in a normal position, and means for moving said lever to move said stem to an operative position. 30

In testimony whereof I affix my signature in presence of two witnesses.

CARL FRED SAMMET.
